Application October 13, 1941, Serial No. 193,751

Term of patent 14 years

To all whom it may concern:

Be it known that I, Arthur Heyman, a citizen of the United States of America and resident of Oakland, county of Alameda, State of California, have invented a new, original, and ornamental Design for a Skirt, of which the following is a specification, reference being had to the accompanying drawing, forming part thereof.

Fig. 1 is a front perspective view of a skirt showing my new design, and

Fig. 2 is a side perspective view of the skirt shown in Fig. 1, in folded position.

The characteristic feature of my design resides in the combination on the skirt disclosed of the stitched pleats extending through the waistband portion on the major portion of the skirt in association with oppositely disposed gores connecting the pleated portions, all as shown.

I claim:

The ornamental design for a skirt, substantially as shown and described.

ARTHUR HEYMAN.
